US00D861825S

(12) **United States Design Patent** (10) **Patent No.:** **US D861,825 S**
Freudenberg et al. (45) **Date of Patent:** **** Oct. 1, 2019**

(54) **INSECT TRAP**

(71) Applicant: **Ecolab USA Inc.**, St. Paul, MN (US)

(72) Inventors: **Jared Ryan Freudenberg**, Plymouth, MN (US); **Matthew Burton Rhodes**, Minneapolis, MN (US); **Ryan Joseph Drake**, White Bear Lake, MN (US); **Joshua James Lanz**, Rochester, MN (US); **Daniel Davis Anderson**, Eagan, MN (US)

(73) Assignee: **Ecolab USA Inc.**, St. Paul, MN (US)

(**) Term: **15 Years**

(21) Appl. No.: **29/645,203**

(22) Filed: **Apr. 24, 2018**

Related U.S. Application Data

(62) Division of application No. 29/565,498, filed on May 20, 2016, now Pat. No. Des. 818,559.

(57) **CLAIM**

The ornamental design for an insect trap, as shown and described.

DESCRIPTION

FIG. 1 is a top, left, front perspective view of an insect trap according to the new design;

FIG. 2 is a front view of the insect trap of FIG. 1;

FIG. 3 is a back view of the insect trap of FIG. 1;

FIG. 4 is a right side view of the insect trap of FIG. 1;

FIG. 5 is a left side view of the insect trap of FIG. 1;

FIG. 6 is a top view of the insect trap of FIG. 1; and,

FIG. 7 is a bottom view of the insect trap of FIG. 1.

The broken lines, areas within them, and the areas adjacent to solid lines and shading depict portions of the insect trap that form no part of the claimed design.

1 Claim, 7 Drawing Sheets
